APPARATUS FOR MULTIPHASE VIBRATION

Robert William Baily, Narberth, Pa.

Application February 13, 1939, Serial No. 256,249

15 Claims. (Cl. 259—1)

An object of my invention is to provide an apparatus for imparting to a material which becomes plastic, or increases in plasticity, when vibrated, vibrations at higher frequencies than heretofore available.

Thus one object of my invention is to provide a simple apparatus for vibrating plastic materials, including a prime mover of comparatively low speed, a vibrator and means for obtaining 10 relatively high vibrating frequency in the vibrator itself.

Another object of my invention is to provide an apparatus for imparting to a material which becomes plastic when vibrated, a plurality of 15 phases of vibrations, some of which are at high frequencies, other vibrations at higher frequencies, and if desired, still other vibrations at still higher frequencies, all from one apparatus, simultaneously.

20 An object of my invention is to provide a vibratory apparatus for utilizing a prime mover of comparatively low speed, and means for obtaining a high frequency of vibration in the vibratory member, and also a plurality of high frequencies of vibration in the member simultaneously. My invention permits a new combination and utilization of some devices already obtainable on the open market, with other devices of my invention, to provide the step-up or 25 increase of speed desired between the prime mover and the out-of-balance weight or weights in the vibratory member, in order that the apparatus may be economical to manufacture and operate, and easy to repair.

30 A further object of my invention is to provide an internal vibrator more powerful in proportion to its weight and diameter than vibrators heretofore available, of higher practicable frequency, and to provide multiphase vibrations 35 which heretofore have not been available in one apparatus.

Another object of my invention is to provide an apparatus for expediting the chemical combination of various materials by subjecting the molecules thereof to a variety of high frequency vibrations simultaneously from one mechanism, obtaining a result similar to that obtained by the 40 use of catalysts.

Portland cement concrete, for instance, contains 45 four principal materials: Coarse aggregate, sand, Portland cement and water. These materials may be used in varying proportions, by selection, the proportion of each which is intended best to accomplish the desired resulting concrete 50 taken into consideration the cost of the ingre-

dients, the ultimate crushing and transverse strength of the set concrete, the impermeability and density of the mass, and so on.

At the time of combining these ingredients in a mixture, and for a reasonable period thereafter, 5 the mass becomes fluid and flowing when subjected to vibration. Obviously a certain proportion of the water is required for hydration of the cement. Additional water is usually placed in the mixture to provide for lubrication of the 10 mass to facilitate placing the mixture in the forms or in its final location. I have found that where vibration is applied to the mixture in the forms during the period of depositing the mixture, the proportion of water may be greatly reduced, so 15 that with vibration a mixture so stiff that it cannot otherwise be successfully placed by any other known method, flows freely to position while vibrated. Furthermore, entrapped air is 20 liberated, and even a large proportion of the remaining water is expelled from the mass. The result is an extremely dense mass. I have also found that a considerable proportion of the cement can be omitted and the resulting concrete 25 will be stronger and denser than the richer mixes which are not vibrated.

I have also found that the larger particles in the mixture, such as the coarse aggregate, are agitated best by comparatively low frequencies of vibration that do not efficiently agitate the 30 finer particles, such as the sand. I have also found that frequencies which best agitate the sand are too low to agitate efficiently the almost impalpable particles constituting the cement. I have found that by imparting to the mass a 35 variety of frequencies of vibrations simultaneously, I am able to agitate all the particles of the mass in the most efficient manner. By the use of my method of imparting a plurality of phases of vibration at different frequencies to a given 40 mass, I obtain a denser and stronger concrete, I am able to reduce the proportion of the most expensive ingredient—cement—I am also able to place a given quantity of the material in a shorter time; I am able to accomplish this result with less labor; and I am also able to remove the containing forms much earlier thereby 45 reducing the investment in form material since the forms can be re-used sooner. Likewise I find that the concrete attains its strength, due to my method of treatment, much earlier than when treated by other methods, all of which permits earlier completion of a given structure.

I have also found that in a liquid that contains in suspension, particles of varying mass and 55

size, certain frequencies of vibration cause the coarser and larger and heavier particles to coalesce, so that their combined mass causes these masses to be efficiently precipitated out of the liquid. I have found that smaller particles remain in suspension, and that when I increase the frequency of vibration, these smaller particles in turn coalesce into larger masses which are quickly precipitated out of the liquid. I have found that when I impart to the liquid two or more frequencies of vibration simultaneously, each frequency being suitable for the suspended matter it is desired to attack, that the different kinds of suspended particles are simultaneously caused to be precipitated from the liquid. In the manufacture of tinplate, for example, the oil used in the bath becomes heavily impregnated with impalpable particles of tin, iron and other impurities of widely ranging sizes and specific gravities. I have found that I can cause the particles of iron to become precipitated by one frequency of vibration, and the tin particles by another frequency of vibration. By imparting both frequencies of vibration simultaneously, I am able to precipitate both metals during a single period of treatment.

I have also found that in the chemical industry there are many processes in which it is desired to cause various chemical elements to combine rapidly. In many processes a catalyst is used to expedite the process. I have found that by subjecting the mixture to a combination of various frequencies of vibration simultaneously, I am able to bring the molecules of the different elements so closely together that the chemical action is expedited in the same manner as if a catalyst were used without vibration. I have also found that where catalysts are used, their action is expedited by the addition of vibrations.

Also to be included among the objects of my invention is the provision of a flexible joint in the flexible shaft or cable which connects the vibrating housing to a motor in order that that shaft may be made of any length and may be hauled about a job without danger of kinking or otherwise damaging the shaft while in operation and contemplated with relation to this object is the provision of such a joint which can, by removing portions of the joint, be used to form a flexible connection for the vibrating housing itself. The effect in utilizing the device in this way is that of a flexible handle for the vibrating element.

With these and other objects in view, my invention consists in the construction, arrangement and combinations of the various parts of my apparatus and in the practice of my methods, whereby the objects contemplated are attained, as hereinafter more fully set forth, pointed out in my claims, and illustrated in the accompanying drawings, in which:

Figure 1 is a vertical cross sectional view of one form of my apparatus.

Figure 2 is a horizontal cross sectional view of my apparatus taken on line 2—2 of Figure 1.

Figure 3 is a vertical cross sectional elevation of another form of my apparatus.

Figure 4 is a horizontal cross sectional view of the apparatus of Figure 3 taken on the line 4—4.

Figure 5 is a graph of the forces separately and combined generated in the apparatus of Figure 3.

Figure 5a shows a position of the weight 65 of Figure 3 in the operation of the device.

Figure 5b shows a later position of the weight 65 of Figure 5a.

Figure 5c shows a later position of the weight 65 of Figure 5b.

Figure 5d shows a later position of the weight 65 of Figure 5c.

Figure 5e shows a position of the weight 35a of Figure 3 during the operation of the apparatus.

Figure 5f shows a later position of that weight 10 during the operation.

Figure 5g shows a still later position of the weight 35a during such operation.

Figure 5h shows a still later position of the weight 35a during such operation.

Figure 6 is a vertical cross sectional view of another form of my apparatus.

Figure 7 is a transverse cross section of the out-of-balance weight shown in Figure 6, taken on the line 7—7.

Figure 8 is an elevation, partly in section, of a modified structure of parts shown in Figure 7.

Figure 9 is a transverse cross section of the propelling ball carrier of Figure 6, taken on the line 9—9.

Figure 10 is a transverse cross section taken on line 10—10 of Figure 8.

Figure 11 is an end elevational view of another form of my apparatus.

Figure 12 is an elevation of my apparatus, 30 equipped with a flexible handle.

Figure 13 is an elevation partly in section on the line 13—13 of Figure 12, illustrating the attachment of the handle to the vibrator casing.

Figure 14 is a sectional view taken on the line 14—14 of Figure 13, illustrating the manner in which two sections of the handle are connected to insure free rotation of the encased shaft.

Figures 15 and 16 are a plan view and sectional view, respectively, of the lock washer used 40 in Figures 6 and 13.

Referring to Figure 1, I provide a housing 1, which may be tubular in form, having the closed lower end 2. A pin 3 is fixed within the end 2 and extends vertically from the inner surface of the cap 2. The pin 3 terminates preferably in the frusto-conical end 5. The upper end of the housing 1 is closed by the end cap 7 engaging the housing 1 by threads 8 or by any other suitable means. To the upper boss 9 and cap 7 is secured the sleeve 10 held in place by the constricting means 11, which causes the material of sleeve 10 to engage corrugations 12 of the boss 9. Extended through the bore 13 of the cap 7, I provide the power shaft 14, which may be rotated by the flexible shaft 15 connected to any suitable source of power. A joint 200 incorporating a sliding drive spindle is shown connecting shafts 14 and 15, the details of which will be described in connection with Figure 6.

The lower end 16 of the shaft 14 terminates in the fitting 17 which carries the inner race 18 of the ball bearing 19 whose outer race 20 is free to move axially but not rotatively in the inner surface 21 of the housing 1. Above the outer race 20 and bearing thereagainst is the annular flange 22 of the flat pusher ring 23.

Above the ring 23 I provide the pressure spring 24 which at its upper end presses against the lower face of the cap 7, and at its lower end bears against the ring 23. The result is to cause the ring 23 to press against the outer race 20 and cause it to have a tendency to move axially downward. Through the ball bearing 19 this movement is transmitted to the fitting 17.

Extending downwardly from the central part of fitting 17 are spaced ears 30 (one being omitted in the drawing). The ears 30 carry the pin 31 which passes through the block 32, in a horizontal direction. The pin 31 passes through the body of a pin 33 as well as through the block 32 and the ears 34 of the weight 35. The parts 30, 31, 32, 33 and 34 form a universal coupling whose center of angularity 37 is at the intersection of the axis 10 of the pin 31 with the long central axis in the housing 1. The weight 35 is therefore free to oscillate in any direction about such center, either laterally, horizontally or with its axis 39 traveling a conical path about the axis 38 of the 15 housing 1. Likewise the weight 35 will revolve about its own axis 39 at an angular rate equal to the angular rate of rotation of the power shaft 14 about the axis 38.

At the lower end of the weight 35 I provide the frusto-conical recess 41 whose face may converge toward the center 37. The diameter of the recess 41 will be greater than the diameter of the pin 3. The wall of the recess 41 makes rolling contact with the pin 3, and the direction of the 20 force of contact is indicated by the arrow 44. The center of gravity or mass of the weight 35 occurs at the point 45 on the axis 39.

Within the weight 35 I provide the bore 46 which receives the shank 47 of the crank 48, 25 and the bore 46 is concentric with axis 39. The cheek 49 of the crank 48 extends downwardly from its shank 47 and terminates in the annular ring bearing 50 which receives the cylindrical portion of the pin 3. The axis of the bearing 30 ring 50 is the axis 38.

The shoulder 51 of the crank 48 does not engage the weight 35. The crank 48 is provided with the boss 54 concentric with the axis 38 and engaging the end of the pin 3. Therefore 35 the shank 47 of the crank 48 may move along the axis 39 within the bore 46 of the weight 35.

It will be seen that the face of the recess 41 makes the angle A with the axis 38 of the pin 3. It will also be seen that the crank 48 maintains the angle A, not permitting the angle to increase or decrease. Pressure in the direction of the arrow 28A will therefore create a wedging action bringing the face of the recess 41 into high pressure contact with the curved conical 40 face of the pin 3. Pressure in the direction of the arrow 28A is provided by the pressure spring 24 of Figure 1 acting through the fitting 17, thence through the universal coupling to the weight 35. I make the spring 24 of such strength 45 that it induces sufficient pressure at the point 43 to create rolling contact between the weight 35 and the pin 3 and prevents sliding contact. Therefore as the weight 35 is rotated about its own axis 39, the face of the recess 41 must roll 50 upon the tapered face of the pin 3.

In Figure 1 I show the weight 35 having the recess 41 with its face making contact at the point 43 with the surface of the pin 3. I also show the cheek 49 which carries the annular 55 bearing 50 engaging the pin 3.

In Figure 3 I show a modified form of my apparatus of Figure 1, the similar parts bearing the same index numerals with the addition of a. In Figure 3 the power shaft 14a terminates at its lower end in the fitting 11a which carries the inner race 18a of the bearing 19a whose outer race 20a is free to move axially but not rotatively in the inner surface of the housing 1a. Extending below the fitting 11a is the eccentric weight 65 60 which joins with the fitting 11a. The ring 69

bears against the top of the outer race 20a. The upper portion 11 of the ring 69 has the pockets 12 which contain the pressure springs 13. The springs 13 bear against the lower face of the cap 1a, and against the lower end of the pockets 12, 10 causing the ring 69 to exert pressure against the outer race 20a. Through the balls and the inner race 18a this pressure is transmitted to the fitting 11a, and thence through weight 65 to fitting 17b, and from there downward through the universal joint 36a to the weight 35a, where the action is the same as that described for Figure 1. Obviously the weight 65 is part of the shaft 14a and the fittings 11a and 17b, and all must revolve at the same angular rate as the shaft 15a, and 15 about the axis 38 of the housing 1. On the lower end of the weight 65 is the fitting ring 17b (similar to 11a) carrying an inner ball race 18b of a ball bearing 19b having the outer race 20b movable axially but not rotatively in the housing 1a. 20

The center of gravity 66 (Figure 4) of the weight 65 travels in a circle 67 having its center in the long axis 38 of the housing 1a. The acceleration or centrifugal force of the weight 65 is in a direction radially from the center of that 25 circle.

Operation

Figure 5 is a graph or diagram showing the centrifugal forces generated by the weights 35a 30 and 65 of Figure 3 as they revolve about the axis 38, taking into account only those vectors of the forces perpendicular to one diametral plane on axis 38 of Figure 3, and showing the resultant vector sums at various sequences of the revolutions of the weights 35a and 65. 35

It is obvious that the radial distance of axis 39 from axis 38 remains constant, as shown in Figure 5e. Therefore the axis 39 will travel in a circular path about the axis 38. Based on the 40 relative dimensions chosen for this illustration, when the weight 35a is revolved 120 degrees about its own axis 39, the point T¹ on the inner surface 41 of the weight 35a will travel to location T². Upon another 120 degrees of revolution 45 of weight 35a, point T¹ will travel to location T³ and so on.

It is later shown that with the relative dimensions chosen for this illustration, the axis 39 will travel around the axis 38 three times as fast 50 as the rate of rotation of weight 65 about the axis 38.

Figure 5a shows the weight 65 in a position generating force F¹ of Figure 5. As weight 65 revolves about axis 38 in Figures 5a, 5b, 5c and 5d, 55 it generates centrifugal forces of the magnitude and directions shown in Figure 5 at F¹, F², F³ and F¹⁰ respectively. Their vectors in direction of line RO generate the sine curve F of Figure 5. 60

As the weight 35a revolves about axis 38 in Figures 5e, 5f, 5g and 5h, it generates centrifugal forces of the magnitude and direction shown in Figure 5 at H¹, H¹⁰, H² and H⁴ respectively. Their vectors in direction of line RO generate 65 the sine curve H of Figure 5.

It will be noted that one position of the weight 65, as shown in Figure 5a is taken at the same instant as the position of the weight 35a of Figure 5e.

When the weight 65 rotates from its position shown in Figure 5a through ninety degrees to its position in Figure 5b, the weight 35a will rotate from its position in Figure 5e, through 270 degrees to its position in Figure 5f. Likewise as 70 75

the weight 65 travels another ninety degrees to its position in Figure 5c, the weight 35a will travel another 270 degrees to its position in Figure 5g. The relative motions of the weights 65 and 35a continue in the same degree.

The vector sum parallel to line RO of force generated by weight 65 shown as curve H of Figure 5 and force generated by weight 35a shown as curve F, produces the curve FH. It will be seen that the housing 1a of Figure 3 will attain a plurality of phases of motion on one diametral plane passing through axis 38. Similar phases of motion at 90 degrees later time will be imparted to the housing 1a by the forces perpendicular to a second diametral plane passing through axis 38 and located at ninety degrees angle from the first diametral plane. It will be seen that the housing 1a will vibrate in a plurality of phases or frequencies due to the difference between the rates of rotation of weights 65 and 35a of Figure 3.

With the radii of the pin 3 and of the recess 41 chosen for this illustration, it will be seen that when the radius a of the weight 35 has revolved about its axis 39 through an arc of 120 degrees, the axis 39 itself will have traveled in the same angular direction on the circle 43 of the circumference of pin 3 through an arc of 360 degrees; in other words, the axis 39 will revolve about the axis 38 three times as fast in angular measurement as the radius a revolves about its own axis 39.

If the diameter of the pin 3 be denoted by the letter d , and the diameter of the wall or inner face of the recess 41 be denoted by the letter D , and if the revolutions per minute of the arrow 59 about the axis 39 be denoted by the letter P , and if the revolutions per minute of the axis 39 about the axis 38 be denoted by the letter O , then

$$O = P \times \frac{D}{D-d}$$

In Figure 5, D was chosen as having a magnitude of 3 units, and d having a magnitude of 2 units, giving $O=3P$

Obviously the center of gravity of the weight 35 lies at the point 45 of Figure 1 on the axis 39, and the acceleration or centrifugal force generated by the weight 35 is in the direction radially outward from the axis of the housing as indicated by the arrow 61 of Figure 1.

Obviously the weight 65 revolves at the same angular rate as the shaft 14, while, as shown in Figure 5, the axis 39 of the weight 35 will revolve three times as fast in angular measurement about the axis 38 under the dimensions chosen for this description. Therefore the weight 35a will make three revolutions about the axis 38 for each revolution of the weight 65 about the axis 38.

Obviously any other ratio of the diameters D and d can be selected to produce any desired relative speed of the weights 35 and 65, provided that D minus d is greater than unity, and it will become apparent also that the circumferential distances will have the same proportion as the diameters.

The centrifugal force of the weight 35 in the direction of the arrow 61, which rotates about the axis 38 in a horizontal plane, imparts an oscillating motion to the housing 1, the frequency of this motion being the same as the number of revolutions of the axis 39 about the axis 38.

Likewise, the centrifugal force of the weight 65

in the direction of the arrow 63, which also revolves about the axis 38 in a horizontal plane, imparts an oscillating motion to the housing 1, the frequency of this motion being the same as the number of revolutions of the center of gravity 56 of the weight 65 about the axis 38.

In Figure 5 at the right, I show diagrammatically the directions and magnitude of the centrifugal forces of the weights 35 and 65 of Figure 3, acting radially away from the axis 38 10 and revolving about the axis 38. The forces generated by the weight 35 are indicated by the arrows H1, H2, and so on up to H12. Likewise the forces generated by the weight 65 are shown by the arrows F1, F2 and so on up to F12. These 15 are taken in sequence assuming rotation in the direction of the arrow 59. The vertical components of the forces are taken in the directions of the arrows 15 and 16.

In Figure 5 I have also shown diagrammatically the relation of the forces with each other with respect to time. For instance, at the time indicated by RO the vertical component of the force H1 is zero and appears in Figure 5 at H1 on the line RO. The vertical component of the same force at H2 appears on the sine-curve at H2, and so on, generating the curve H which rises to H4, then passes downwardly through H7 to the low point H10 thence upwardly through H1 on the line R1, and continues in the same 30 manner. The distance aa to bb represents the time involved in one revolution of the axis 39 of the weight 35 about the axis 38 of the apparatus.

During the same period the vertical components F of the force generated by the weight 65 will form the sine-curve F of Figure 5. Since the weight 65 revolves, as assumed for this illustration, at one-third the speed of the weight 35, the sine-curve F will commence with a value of zero at the line RO, will rise to the point F4, thence go downwardly through the point F7 to the low point F10 and rejoin the line H at the line R3. The distance FR1 indicates the time involved in one revolution of the weight 65, and 45 is equal in this illustration to the time required for three revolutions of the weight 35.

The cumulative effect of the centrifugal forces generated by the weights 35 and 65 are shown in the curve FH which is the summation of the 50 forces indicated by the curves F and H. The curve FH indicates the amplitude of movement imparted to the housing 1 of Figure 1 by the revolving weights 35 and 65.

From this description it will be obvious that 55 that housing 1 of Figure 3 will impart to any material in which it is immersed, a variety of frequencies of vibration and at various amplitudes. The relative rate of rotation of the weights 35 and 65 may be selected by varying 60 the diameters D and d of Figure 1, so that any desired combination of frequencies and amplitude may be obtained.

In Figure 6 is shown another form of my apparatus. The housing 100 has its lower end closed by cap 102 and the upper end cap 103 secured to the upper end of the housing 100 by the threads 104. To the upper boss 103a of the cap 103 may be secured a sleeve like the sleeve 10 above described. In the annular bore 105 of the cap 103 is the power shaft 106 which may be rotated by a flexible shaft connected to any suitable source of power.

For the purpose of this description it may be 75

considered that the power shaft 106 rotates clockwise when viewed from above. The lower part of the shaft 106 is somewhat enlarged as shown at 107 and the upper portion of such enlarged part is threaded.

The enlarged part 107 of the shaft 105 is carried in anti-friction ball bearings 108 and has below them the annular shoulder 109 below which is the head 110. The shouldered portion 109 carries the propelling ball carrier 111 having the downwardly projecting circumferentially spaced fingers 111a. A nut 112 threaded on the upper part of the enlarged portion 107 of the shaft 106 clamps the inner race of the ball bearing assembly 108 and the ball carrier 111 together to make them non-rotatable with respect to each other.

Within the housing and surrounding the ball bearing assembly 108 and the upper part of the ball carrier 111 is a sleeve 113. The sleeve 113 is permitted limited movement lengthwise of the housing 100 but is held against rotary movement by means of a pin 114 mounted in the wall of the housing 100 and projected into a vertically elongated slot 115 in the outer face of the sleeve 113 at the upper end of the sleeve.

In the cap 102 is received a ball bearing assembly 118 which is permitted certain movement axially of the housing 100. The bearing assembly 118 receives the lower end of a shaft 119. On the shaft 119 below the bearing assembly 118 is a threaded nut 120. On the shaft 119 above the bearings 118 is the out-of-balance weight 121 which has the upwardly projecting spindle or shaft 122 on which is a clamping nut 123 herein-after again referred to.

The particular type of lock washer is designed for securing the inner rings of the bearing assembly 108 to the enlarged portion 107 of the shaft 106. This construction takes the form of a lock nut 112 which is adapted to be threaded upon the enlarged portion 107 in order to press the inner rings of the bearing assembly against the upper surface of the ball carrier 111. In order to hold the lock nut in place there is provided a washer 160 which has a lug 161 in the inner circumference thereof and a plurality of spaced lugs 162 at the outer circumference.

There is provided on the enlarged portion 107 a longitudinal slot 163 which extends beneath the inner ring of the bearing assembly and into this slot the lug 161 is projected to prevent rotation of the washer with respect to the enlargement.

The lock nut itself has provided therein a plurality of recesses 164 which are adapted to receive the turned up ends of the outwardly projecting lugs 162 and thereby tightly lock the washer and nut in place whenever the proper tension has been placed upon the bearing assembly by screwing the nut downwardly upon the threaded section of the enlarged portion 107. A similar type of lock washer is used for the next lower lock nut.

On the shaft 122 is the angular type ball bearing indicated generally by the numeral 124. The inner bearing 125 of the ball bearing 124 rests against the shoulder 126 of the weight 121. The balls 127 with their carrier 128 run in the outer race 129 which bears against a shoulder 130 in the housing 100, whereby the bearing 124 is held against movement downwardly. Above the inner race 125 is the separator ring 131 upon which rests the inner race 132 of a ball bearing indicated generally at 133 having the outer race 134

and the balls 135 engaged by the fingers 111a of the ball carrier 111. Pins 136 extend into the outer race 134 and into the sleeve 113 and thus hold the outer race against rotation.

In Figure 7 is shown a section of the weight 121. The center of gravity of the weight 121 is indicated by the point 137. The rotating axis of the weight 121 is the same as the long axis 38' of the housing 100.

Before completing the description of the ball carrier 111, I will refer to Figure 8 which shows a slightly modified form of device which may be used with the structure shown in Figure 6. In Figure 8 I have shown, instead of the power shaft 106, a power shaft 138 which is provided with the out-of-balance weight 139, the center of gravity of which is at point 140 in Figure 10. Where the shaft 138 and weight 139 are used and rotated, the weight 139 will create a centrifugal force radially outwardly. The rate of angular rotation of the weight 139 about the axis 38' will be the same as the rate of rotation of the shaft 106, Figure 6, under similar conditions. The rotation of the weight 139 will cause oscillation of the housing 100 at the frequency of rotation of the weight about the axis 38'.

Where the form of device shown in Figure 8 is used, a ball bearing 141 shorter than the ball bearing shown above the ball carrier in Figure 6 is employed and below the weight 139 I provide a ball bearing 142 below which is a ball carrier 143 similar to the ball carrier 111 and similarly associated with the ball bearing 132.

The sum of the affects of the two weights 121 and 139 upon the housing 100 corresponds exactly to the conditions and results described with the apparatus shown in Figure 3. In other words, the arrangement of the device shown in Figure 6 when equipped with the form of device shown in Figure 8 will produce multiphase vibrations and frequencies in the housing 100 which will in turn be transmitted to any surrounding material, such as concrete.

I will now refer to the operation and construction of the ball carriers 111 and 143. Referring to Figure 6 it will be seen that the sleeve 113 exerts a downward thrust against the outer ball race 134. The inner race 132 of the same bearing may not move downwardly since it is supported by the separator 131 and the bearing 124. The balls 135 therefore become wedged between the conical face 144 of the outer race 134 and the conical face 145 of the inner race 132. The pressure on the balls 135 is exerted on their diameter 146. The springs 117 are of such strength and under such compression that the exerted pressure on the diameter 146 forces the balls 135 to make rolling contact with the races 132-134 and prevents sliding contact.

I shall now refer to Figures 6 and 9 and it may be remembered that the ball carrier 143 of Figure 8 is the same as ball carrier 111 of Figure 6. The non-rotatable outer race 134 engages and exerts pressure on the balls 135 at the points 147 and through the balls to the points 148 on the inner ball race 132. As the shaft 106 rotates, the propelling ball carrier 111 is rotated in the same angular direction. The fingers 111a of the ball carrier thus obviously rotate around the axis 38' in the same angular direction. The fingers 111a will exert pressure against the balls 135 and tend to move the balls in the direction indicated by the arrow 150. Since the balls cannot slide in the races 134 and 132, they will rotate about their 75

centers in the direction indicated by the arrow 149.

Friction at the point 148 on the inner race 132 will cause the inner race to rotate in the direction of the arrow 150 about the axis 38'. The angular rate of rotation of the inner race 132 and the shaft 122 which is fixed to the inner race will exceed the angular rate of rotation of the ball carrier 111 and its shaft 106.

- 10 The amount by which the rate of rotation of the shaft 122 exceeds the rate of rotation of the shaft 106 is determined by the selection of the diameter of the balls 135, the diameter of the inner face of the race 134 and the diameter of 15 the face of the race 132 which engages the balls.

In the drawings I have selected dimensions in which the increase is in the ratio of 3 to 1 for the purposes of my description.

Under the conditions stated, the shaft 122 will 20 rotate the weight 121 about the axis 38' three times the angular rate of rotation of the power shaft 106. The direction of acceleration or centrifugal force of the weight 121 is indicated by the arrow 149 in Figure 7 and the force will cause the 25 housing 100 to oscillate at the frequency of rotation of the weight 121 about the axis 38'. The connection, therefore, between the vibrating portions of the shaft at this point is in the 30 nature of a step-up or speed change clutch adapted to drive the lower shaft at a greater speed than the drive shaft. It can readily be appreciated, however, that a step-down clutch could be made following these principles which would have the reverse effect.

35 In Figure 11 I show a clamp for mounting the housings 1, 1a or 100 on a form or container for plastic material or any member to be vibrated. The clamp has the members 151 and 152 adapted to be secured together by screw bolts 153. 40 The clamp member 152 has a base 154 that may be bolted or otherwise secured to a form 155, or placed on plastic material. Thus the material whether in a form or container will be subjected to the single phase vibrations of the apparatus of Figures 1 and 6 or the multiphase vibrations of the apparatus of Figures 3 and 8 when the latter is used with the apparatus of 45 Figure 6.

In vibrating apparatus of this sort which is 50 operated by means of a flexible shaft or cable 170 (Figure 12) it frequently becomes necessary to provide some means in the cable which will add to its flexibility especially where the cable might be one of considerable length attaching a 55 vibrating casing 185 to a motor 169 and subjected to considerable bending during use. A flexible joint of this sort shown in Figures 12 and 14 comprises a separable hollow casing generally designated 172 comprising a part consisting of a mid section 172' and parts 173 and 174 connected to adjacent ends of the outer sleeve 10' of the flexible shaft 170 as for example by use of a set screw 182.

The flexible shaft itself is confined within the 60 outer sleeve 10', one element of which is indicated by the reference numeral 175 and another element of which is indicated by the reference character 175'. To provide the flexible portion of the joint there is secured to the shaft element 175' for example a hollow sleeve 176 which is rotatably journaled within the casing 172 by means of ball bearing assemblies 177 and 178. To the other shaft element 175 there is attached a projection 179 which extends in a somewhat 65 telescopic like arrangement within the sleeve 176.

The sleeve is provided with a key 180 extending inwards thereof and in the projection 179 there is provided an elongated longitudinal slot 181 adapted to receive the key 180 and permit it to move endwise thereof while at the same time preventing relative rotation between parts. In an arrangement of this sort as the elements of the flexible shaft may be shifted slightly in an endwise direction they are permitted freedom of movement while at the same time being secured non-rotatably one with the other.

10 A portion of the same connection can be utilized as a flexible joint for the vibrating housing itself as shown in Figure 13. When the joint portion is to be used in this manner the part 173' is retained while the remaining parts, namely, the mid portion 172' and 174 are removed. A flexible shaft or cable 170' of the kind previously described is attached by some suitable means to the part 173'. Within the cable 20 173' there is provided a projection 179' to which is attached an element of the flexible shaft which leads from the motor.

When a vibrator housing such as the housing 185 is attached in this manner it is provided with 25 an end member 186 attached to the housing at one end and attached threadably to the part 173' at the other. The vibrating mechanism within the housing may be of the sort previously described in this application, consisting 30 primarily of ball bearing assemblies 187 operating about an enlarged part 188 of a sleeve-like shaft element 189. Upon the shaft element there is attached the customary locking nut 190 together with the other portions of the device 35 previously described, as shown in Figure 13. The projection 179 to which the flexible shaft element is attached is provided with an elongated longitudinal slot 191 similar to the slot 181 in Figure 14 and this slot is designed to receive a key extending therewith from the portion 40 of the sleeve-like shaft element 189.

The operation of this flexible connection for the vibrator portion itself is similar to that described for the flexible joint shown in Figure 14 45 in that the telescopic projection 179' and sleeve-like shaft element 189 can move endwise with respect to each other but are fastened non-rotatably together so that there is a positive drive from one to the other in a rotary direction.

50 In the operation of my method I insert the apparatus either wholly or partially into the material to be vibrated, or I bring the apparatus into contact with a container containing the material, or I bring the apparatus into contact with the 55 surface of the material to be vibrated, while the apparatus is vibrating. I may either allow the apparatus to remain suspended in, or in contact with the material, or in contact with the container, or I may move the apparatus about in or on or 60 against the material in a manner which I may deem will best accomplish the desired results.

65 In Figure 6 I show the lower end cap 102 carrying the pump screw 156 coincident with the axis 38'. In the shaft 119, the weight 121 and the shaft 122 I provide the bore 157 slightly larger in diameter than the screw 156. The screw 156 is provided with the threads whose pitch is in this case left hand. The well 158 contains a 70 lubricant, and as the weight 121 rotates, the lubricant is forced by the screw 156 to ascend the bore 157 and escapes into the space below the head 110 and flows thence downwardly through the bearings, thence downwardly be- 75

tween the weight 121 and the housing 100 through the bearings 118.

Some changes may be made in the construction and arrangement of the parts of my device without departing from the real spirit and purpose of my invention, and it is my intention to cover by my claims any modified forms of structure, or use of mechanical equivalents, which may be reasonably included within their scope.

10 I claim as my invention:

1. A vibrating device comprising a housing, a drive shaft journalled therein, a weight and a universal coupling for securing said weight non-rotatably to the shaft, a positioning pin for the 5 weight secured within the housing, said weight being provided with a large tapered recess at the free end having a surface therein of predetermined circumference and a complementarily tapered end on the pin provided with a lateral 10 surface having a circumference smaller than the circumference in the recess by a predetermined amount adapted to have one side held in rolling contact with one side of the surface in said recess forming a crescent shaped space therebetween, a loose crank member positioned in said space having surfaces in sliding contact with the 15 surfaces of said pin and said recess adapted to tilt the weight so that the center of gravity is displaced laterally with respect to the axis of said shaft, and means for urging the surfaces into 20 intimate contact so that as the shaft is rotated at a moderate speed the center of gravity of the universally coupled shaft is rotated at a more rapid speed to produce high frequency vibrations 25 in said casing.

2. A vibrating device for producing vibrations at a plurality of frequencies comprising a housing, a drive shaft journalled in the housing, an off-center weight on said shaft adapted to be rotated to produce vibrations of frequency corresponding to the rate of rotation of the shaft, and a second weight having the center of gravity positioned off-center with respect to the axis of the shaft loosely attached to the shaft and guided 40 by a portion of said housing so that the center of gravity thereof is vibrated at a frequency different from that of the first weight and produces cumulative vibrations in the housing of a plurality of frequencies.

45 3. A vibrating device comprising a housing, a rotatable drive shaft journalled therein, a weight and a universal coupling for securing said weight non-rotatably to said drive shaft, a positioning pin in the housing adapted to hold the weight 50 off-center from the axis of the shaft, and coacting rolling contact surfaces on the weight and the pin adapted to cause rotation of the weight and consequent vibration of the housing at a rate different from the rate of rotation of the shaft, and an off-center weight rotated synchronously with said shaft adapted jointly with said first weight to generate compound vibrations of a 55 plurality of frequencies in the housing.

60 4. A vibrating device comprising a housing, a rotatable drive shaft journalled therein, a weight and a universal coupling for securing said weight non-rotatably to the shaft, a positioning pin for 65 said weight secured within the housing adapted to tilt said weight so that the center of gravity thereof is off-center with respect to the axis of the drive shaft, coacting tapered surfaces of 70 different diameters on said weight and said pin adapted to form a progressive rolling point of contact therebetween and means for maintaining 75 said contact so that the axis of the weight is

displaced at a predetermined angle with relation to the axis of the drive shaft, said weight being adapted to be rolled about the positioning pin at an angular rate different from the rate of rotation of said drive shaft to produce oscillating 5 vibrations of a desired frequency in said housing and a second off-center weight secured to the drive shaft adapted to be rotated at the same speed as the shaft and productive with said first weight of cumulative composite vibrations of a 10 plurality of frequencies.

5. A vibrating device comprising a housing, a drive shaft journalled therein, a weight and a universal coupling for securing said weight non-rotatably to the shaft, a positioning pin for the 15 weight secured within the housing, said weight being provided with a large tapered recess at the free end having a surface therein of predetermined circumference and a complementarily tapered end on the pin provided with a lateral surface 20 having a circumference smaller than the circumference in the recess by a predetermined amount adapted to have one side held in rolling contact with one side of the surface in said recess forming a crescent shaped space therebetween, a loose 25 crank member positioned in said space having surfaces in sliding contact with the surfaces of said pin and said recess and having a surface in rolling contact with a surface on the pin, said crank member being adapted to tilt the weight 30 so that the center of gravity is displaced laterally with respect to the axis of said shaft and means for urging the rolling surfaces into intimate contact so that as the shaft is rotated at a moderate speed the center of gravity of the universally 35 coupled shaft is rotated at a more rapid speed to produce high frequency vibrations in said casing, and a second weight operatively secured to the drive shaft adapted to be driven at the same angular velocity as said shaft and adapted together with the first weight to set up a successive 40 plurality of vibrations of different frequencies in said housing.

6. A vibrating device comprising a housing, a rotatable drive shaft connected thereto, an off-center weight journalled in the housing adapted to be connected to the drive shaft to be rotated thereby in order to vibrate the housing, a connection between said shafts comprising a speed change member comprising bearing rings and 45 bearings mounted therein, one of said rings being connected to the weight and another of said rings being mounted non-rotatably with respect to the housing, means for shifting said rings longitudinally with respect to each other to wedge the 50 bearings frictionally therebetween, and means for driving said bearings at an angular rate determined by the speed of the drive shaft, said bearings being adapted to rotate and drive the inner 55 of said rings and the weight at an angular rate 60 different from the driving means to set up a vibration of different frequency in the housing.

7. A vibrating device comprising a housing, a rotatable drive shaft journalled therein, a weight shaft journalled in the housing adapted to be connected to the drive shaft and an off-center weight adapted to be rotated thereby at an angular velocity different from said shaft in order to vibrate the housing, a connection between said shafts comprising a speed change member comprising a 70 pair of bearing rings and bearings mounted therein, one of said rings being connected to the weight and another of said rings being mounted non-rotatably with respect to the housing and adapted to shift longitudinally with respect to 75

said first ring to wedge the bearings frictionally therebetween, and means on the drive shaft for driving said bearings thereabout at an angular rate of rotation determined by the speed of the 5 drive shaft, said bearings being adapted to rotate in a lateral plane on their respective longitudinal axes and drive the inner of said rings and the weight at an angular rate determined by the ratio of the diameter of said bearings to the diameter 10 of said inner ring to set up a vibration of different frequency by means of said weight.

8. A vibrating device comprising a housing, a rotatable drive shaft journalled therein, a weight shaft journalled in the housing adapted to be 15 connected to the drive shaft and an off-center weight adapted to be rotated thereby at an angular velocity different from said shaft in order to vibrate the housing, a connection between said shafts comprising a speed change member comprising 20 a pair of bearing rings and bearings mounted therein, one of said rings being mounted on the weight shaft and another of said rings being mounted non-rotatably with respect to the housing and adapted to shift longitudinally with 25 respect to said first ring to wedge the bearings frictionally therebetween, means on the drive shaft for driving said bearings thereabout at an angular rate of rotation determined by the speed of the drive shaft, said bearings being adapted to 30 rotate in a lateral plane on their respective longitudinal axes and drive the inner of said rings and the weight at an angular rate determined by the ratio of the diameter of said bearings to the diameter of said inner ring to set up a vibration of 35 different frequency by means of said weight, another off-center weight mounted on the drive shaft adapted to rotate simultaneously therewith and adapted further to generate a set of vibrations at variance with said first weight and produce 40 a compound vibration condition in the housing characterized by a succession of vibrations of varied frequencies.

9. In apparatus of the kind described, a housing having at one end a pin extending into the 45 housing, a weight arranged for rotation within the housing and having an interior track at one end concentric with the axis of rotation of the weight for rolling engagement with the pin, the diameter of the interior track exceeding the diameter of the pin, rotative means associated with the weight for imparting rotation thereto, anti-friction means in the housing and engaging the weight and the pin for maintaining the axis of 50 rotation of the weight in displacement with respect to the axis of the pin, and, in addition to centrifugal force, pressure means causing rolling engagement of the interior track of the weight with the pin at and immediately following commencement of rotation of the weight, the weight revolving on its axis of rotation at approximately the rate of rotation of the rotative means, the center of gravity and the axis of rotation of the weight revolving about the axis of the pin at an angular rate exceeding the rate of rotation of the 55 rotative means, causing impartation to the housing of vibrations at a frequency in excess of the rate of rotation of the rotative means.

10. In apparatus of the kind described, a member to be vibrated and having a pin disposed upon 70 an axis of the member, a weight arranged for rotation about its own axis and also about the axis of the member, the weight having an interior track at one end concentric with the weight axis for rolling engagement with the pin, rotative means associated with the weight for imparting 75

rotation thereto; anti-friction means engaging the pin and the weight for maintaining the axis of the weight in displacement with respect to the axis of the member; and, in addition to centrifugal force, pressure means causing rolling engagement of the interior track of the weight with the pin at and immediately following commencement of rotation of the weight, the weight revolving on its axis at approximately the rate of rotation of the rotative means, the center of gravity 10 of the weight revolving about the axis of the member at an angular rate exceeding the rate of rotation of the rotative means, causing impartation to the member of vibrations at a frequency in excess of the rate of rotation of the rotative 15 means.

11. In apparatus of the kind described, a housing having at one end a pin extending into the housing, a first weight arranged for rotation within the housing and having an interior track 20 at one end concentric with the axis of rotation of the first weight for rolling engagement with the pin, the diameter of the interior track exceeding the diameter of the pin, rotative means associated with the first weight for imparting 25 rotation thereto, anti-friction means in the housing and engaging the first weight, and the pin for maintaining the axis of rotation of the first weight in displacement with respect to the axis of the pin, and, in addition to centrifugal force, 30 pressure means causing rolling engagement of the interior track of the first weight with the pin at and immediately following commencement of rotation of the first weight, the first weight revolving on its axis of rotation at approximately 35 the rate of rotation of the rotative means, the center of gravity and the axis of rotation of the first weight revolving about the axis of the pin at an angular rate of rotation of the rotative means, causing impartation to the housing of 40 vibrations at a frequency in excess of the rate of rotation of the rotative means, a second weight arranged for rotation within and supported by the housing, the second weight having its center of gravity radially distant from its axis of rotation, said second weight axis of rotation being approximately coincident with the axis of the housing, the second weight being operatively associated with the rotative means to cause the second weight to revolve at approximately the speed of 45 rotation of the rotative means, the second weight imparting to the housing vibrations at a frequency approximately similar to the rate of rotation of the rotative means, whereby the housing is vibrated with a plurality of frequencies of 50 vibration.

12. In an apparatus of the kind described, a housing, a plurality of weights arranged for rotation within the housing, a rotative means, each weight arranged for coaction with the rotative means, each weight having its center of gravity radially distant from its axis of rotation, each weight so arranged that it imparts to the housing vibrations at a frequency similar to the rate of rotation of the center of gravity of the weight 60 about an axis of the housing, means for causing the center of gravity of one or more of the weights to revolve about an axis of the housing at an angular rate differing from the rate of rotation of the center of gravity of another of the 65 weights about an axis of the housing, whereby the housing is vibrated with a plurality of frequencies of vibrations.

13. In an apparatus of the kind described, a member to be vibrated and having a rotatable 70

driving shaft, a plurality of rotatable weights associated with the member, each weight arranged for rotation by the driving shaft, each weight having its center of gravity radially distant from the prolongation of the axis of the drive shaft, each weight so arranged that it imparts to the member vibrations at a frequency similar to the rate of rotation of the center of gravity of the weight about the axis, means for causing the center of gravity of one weight to revolve about the axis at an angular rate differing from the rate of rotation of the center of gravity of another weight about the axis, imparting to the member vibrations having a plurality of frequencies.

15 14. In apparatus of the kind described, a housing, a first weight arranged for rotation within the housing and supported thereby, the first weight having its center of gravity radially distant from its axis of rotation, a rotative means associated with the housing and revolving the first weight by means of an epicyclic train to cause the first weight to revolve at an angular rate in excess of the rate of rotation of the rotative means, causing impartation to the housing 20 vibrations at a frequency in excess of the rate of rotation of the rotative means, a second weight arranged for rotation within and supported by the housing, the second weight having its center of gravity radially distant from its axis of rotation, said second weight axis of rotation being approximately coincident with the axis of the

housing, the second weight being operatively associated with the rotative means in a manner to cause the second weight to revolve at approximately the speed of rotation of the rotative means, the second weight imparting to the housing vibrations at a frequency approximately similar to the rate of rotation of the rotative means, whereby the housing is vibrated with a plurality of frequencies of vibration.

15. In an apparatus of the kind described, a 10 housing, a weight arranged for rotation within the housing and supported thereby, the weight having its center of gravity radially distant from its axis of rotation, a rotative means associated with the housing for revolving the weight and 15 means for revolving the weight from the rotative means comprising a speed-increasing epicyclic train having a fixed member, a driving member associated with the rotative means and revolving at the angular speed of the rotative means, 20 a driven member associated with the weight and inducing rotation thereof, intermediate means making non-slidable engagement with the fixed member and the driven member, said driving member propelling said intermediate means 25 causing the weight to revolve at an angular speed in excess of the rate of rotation of the rotative means, thereby imparting to the housing vibrations at a frequency in excess of the rate of rotation of the rotative means. 30

ROBERT WILLIAM BAILY.
